Primary Examiner—Nelson C. Holtje(74) *Attorney, Agent, or Firm*—St. Onge Steward Johnston & Reens LLC(57) **CLAIM**

I claim the ornamental design for the valve with two mounting holes, as shown and described in the drawings.

DESCRIPTION

FIG. 1 is a perspective view of a valve with two mounting holes in accordance with the new design;

FIG. 2 is a back plan view thereof;

FIG. 3 is a front plan view thereof;

FIG. 4 is a right side view thereof;

FIG. 5 is a left side view thereof; and,

FIG. 6 is an upper side view thereof.

The broken line showing s are for illustrative purposes only and form no part of the claimed design.
